ATTORNEY

UNITED STATES PATENT OFFICE

EDWIN ARCHER TURNER, OF NEW YORK, N. Y., ASSIGNOR TO THE STANDARD STOKER COMPANY, INCORPORATED, A CORPORATION OF DELAWARE

STOKER

Continuation of application Serial No. 194,490, filed May 26, 1927. This application filed November 2, 1929.
Serial No. 404,266.

This invention relates to stokers, and more particularly to locomotive stokers.

One of the objects of the invention is the provision of a new and improved fuel conduit for locomotive stokers whereby fuel may be transferred from the tender to the locomotive and forced upwardly into the firebox thereof in a loose condition and with the expenditure of a minimum amount of power.

Another object of the invention is the provision of a new and improved fuel conduit having novel means for preventing rotation of the fuel in the delivery end of said conduit.

A further object of the invention is the provision of a new and improved riser conduit having a delivery end that is adapted to cooperate with the distributing means for efficiently supplying fuel to the back corners of the firebox.

A still further object of the invention is the provision of a new and improved riser conduit having a circular lower end which gradually merges into a form angular in cross-section at its upper end.

Other and further objects and advantages of the invention will appear from the following description taken in connection with the accompanying drawings, in which

Fig. 1 is a longitudinal vertical section of a portion of a locomotive tender and stoker, showing the latter in position;

Fig. 2 is a section on line 2—2 of Fig. 1;

Fig. 3 is a section on line 3—3 of Fig. 1;

Fig. 4 is a section on line 4—4 of Fig. 1.

In stokers having conveyer conduits terminating in a cylindrical riser conduit through which fuel is forced into the firebox of the boiler, the fuel will tend to adhere and form a solid mass if the diameter of the riser is substantially that of the conduit, and on emerging from the upper end of the conduit considerable energy is necessarily expended by the distributing jets in breaking up the mass. Furthermore, the mass will tend to rotate, and the rotation of the mass, the lower end of which is curved rearwardly somewhat, will cause a continual rearranging of the particles at the curved portion of

the riser, thus tending to pulverize the fuel more or less. The friction between the rotating mass and the walls of the conduit will also tend to pulverize the fuel to a certain extent.

All this is objectionable because of the strong drafts employed in locomotives, which tend to carry a great amount of the finer particles through the stack as unconsumed carbon.

The present invention seeks to overcome these difficulties by providing means for preventing packing of the fuel in the delivery end of the conduit, and for preventing the rotation of the mass.

Referring now to the drawings, in which similar reference characters designate the same parts throughout the description, the reference character 10 designates a locomotive having a firebox 11 provided with grates 12. The backhead 13 is provided with the usual firedoor opening 14 and mudring 15. The cab is shown at 16, the deck at 17 and the tender at 18, all of which may be of the usual or any approved construction.

Since the parts thus far described are of the conventional form of construction it is not thought necessary to further illustrate or describe the same.

A suitable conveyor conduit designated generally by the reference character 19 is employed for transferring the fuel from the tender to the locomotive. This conduit is adapted to deliver a single stream of fuel through the grates to the firebox. The forward end of the conveyor conduit is curved upwardly and extends through the grates 12 as clearly shown in Fig. 1 of the drawings.

The conveyor conduit comprises a transfer conduit 21, the forward end of which is preferably curved upwardly as at 22 and is provided with an annular shoulder or seat 23 and a collar or flange 24 for receiving the lower end of the riser or elevator conduit 25 which is supported by said shoulder.

The inner surface of the riser conduit is flush with that of the transfer conduit whereby there is no obstruction to the movement of fuel through said conduits. The parts are held in assembled relation in any suitable

manner as by the bolts or screws 26 extending through said collar into the lower end of said riser conduit.

Fuel transfer means, as the screw conveyor 27, is adapted to transfer the fuel from the tender to the locomotive and force the same upwardly through the riser conduit in front of the steam nozzle 28 where it is distributed over the firebox. It has been found by experiment that the screw conveyor must stop short of the forward wall of the upwardly curved portion of the conduit for otherwise the fuel will be forced against the said wall and become packed in the conduit. The screw conveyor 27 therefore stops short of the front wall of the curved portion of the conduit a sufficient distance to prevent this packing.

It is understood that suitable means are employed to protect the riser conduit from the intense heat of the fire, as is usual in such constructions. Since this feature constitutes no part of the present invention it was not thought necessary to illustrate or describe the same.

The rotation of the screw in forcing the fuel through the riser conduit tends to cause the fuel mass to rotate in said conduit. Suitable means are provided for preventing this rotation. As shown, the upper portion of the riser conduit changes its form in cross-section from its lower portion. The lower portion is circular, while the upper portion is non-circular. The non-circular portion will prevent the mass from rotating.

In the form of construction selected to illustrate one embodiment of the invention, the upper end of the riser conduit is angular in cross-section. It is preferably rectangular.

As shown, the riser conduit 25, which is circular in cross-section at its lower end, as indicated at 31 in Fig. 2, gradually merges into a quadrilateral with curved corners or connecting portions as shown at 32 in Fig. 3, and from the quadrilateral with curved connecting portions into a square in cross-section, as shown at 33 in Fig. 4. The cross-sectional area of the upper end of the riser conduit is slightly larger than at its lower end. The cross-sectional area gradually increases from the bottom to the top of the riser conduit, whereby the fuel is loosened as it ascends. The gradual changing from a cylindrical to a square portion, and the gradual increase in cross-sectional area of the conduit conveyor toward its upper end is conducive to keeping the fuel loose and thus more easily elevated and distributed.

The upper rectangular end of the riser conduit 25 has its forward upper edge parallel with the back wall of the firebox whereby a better distribution of the fuel is insured than where the walls of the riser conduit are circular because a greater portion of the forwardly projected fuel will be moving sub-

stantially normal to said wall when it strikes the same, and hence will not be deflected laterally, whereas with a circular wall a great portion of the forwardly projected fuel will strike the curved portions of the side walls 70 and be deflected toward the center line of the firebox.

Furthermore, the straight side walls will deflect less of the laterally moving fuel forwardly than the curved side walls because 75 the laterally moving fuel will strike the straight walls more nearly normal than it would the rear portions of a curved wall, with the result that fuel is more efficiently supplied to the rear corners of the firebox. 80

This is a continuation of my application Serial No. 194,490 filed May 26, 1927.

It is thought from the foregoing taken in connection with the accompanying drawings that the construction and operation of my device will be apparent to those skilled in the art, and that various changes in size, shape, proportion and details of construction may be made without departing from the spirit and scope of the appended claims. 90

I claim as my invention:

1. In combination, a locomotive provided with a firebox having grates therein, a tender for said locomotive, a fuel conduit having its rear portion extending beneath the floor of said tender and having its forward portion curved upwardly and extending through said grates to a point above the plane thereof, the upwardly extending portion of said conduit being substantially circular in cross-section and gradually increasing in cross-sectional area and merging into a substantially equilateral configuration at its upper end, the front side of said rectangular portion extending transversely of said firebox, a helical screw in said conduit for conducting fuel from said tender and delivering it into said firebox in a single, continuous stream, and means including a steam nozzle located at the rear of the rectangular portion of said conduit for projecting fuel emerging from said conduit in aerial paths over the grates in said firebox. 105

2. In stoker mechanism, a continuous, jointed, single conduit having a curved portion at one end, said conduit being circular in cross-section adjacent to said curved portion and gradually increasing in cross-sectional area and merging into a substantially equilateral configuration toward the end of 110 its curved portion, and a helical screw in the rear portion of said conduit for conducting fuel along the rear portion of said conduit and forcing the same through said curved portion. 120

3. In combination, a locomotive having a firebox provided with grates, a tender for said locomotive, a fuel conduit for transferring fuel from said tender to said locomotive and delivering the same through said grates 130

into said firebox, comprising a rear portion extending beneath the floor of said tender, a connecting curved portion and a single riser portion extending from said curved portion upwardly through said grates to a point above the level thereof, the forward portion of said conduit gradually changing from circular to substantially equilateral form in cross-section toward its upper end, a helical screw in said conduit for conducting the fuel along the same, and means for distributing the fuel in aerial paths over said grates as the same emerges from said riser conduit.

4. In combination, a locomotive having a firebox provided with grates, a tender for said locomotive, a fuel conduit for transferring fuel from said tender to said locomotive and delivering the same to a point above the normal firebed in said firebox, said conduit comprising a rear and a forward portion, said rear portion extending beneath said tender and said forward portion comprising a curved portion and a single riser portion, the upper end of said forward portion being substantially equilateral in cross-section and gradually changing to circular form in cross-section from its upper end toward said curved portion, a rotatable screw conveyor in said rear portion, and a steam distributing nozzle at the rear of the upper end of said riser portion for projecting the fuel delivered by said riser conduit, in aerial paths over the grates of said firebox.

5. In combination, a locomotive provided with a firebox having grates therein, a sectional fuel conduit having its rear portion extending beneath the floor of said tender and having its forward portion curved upwardly and extending through the grates of said firebox to a point above the normal level of the firebed in said firebox, the forward upper end of said conduit being substantially equilateral in cross-section and gradually decreasing in cross-sectional area and merging into circular form in cross-section toward the curved portion, a rotatable screw in said rear portion and terminating short of the forward wall of the curved portion a sufficient distance to prevent impacting of the fuel, and a steam nozzle for projecting the fuel forwardly and laterally in aerial paths over said grates as the same emerges from said conduit.

60 55 In testimony whereof I affix my signature.
EDWIN ARCHER TURNER.
